(57) **CLAIM**

The ornamental design for a console/terminal for use in digital data based systems, as shown and described.

DESCRIPTION

FIG. 1 is a front, top and right side perspective view of a first embodiment of the computer terminal showing the new design;

FIG. 2 is a top plan view thereof;

FIG. 3 is a front elevation view thereof;

FIG. 4 is a rear elevation view thereof;

FIG. 5 is a left side view, the right side being a mirror image thereof;

FIG. 6 is a front, bottom and left side perspective view thereof;

FIG. 7 is a front, top and right side perspective view of a second embodiment of the computer terminal showing the new design;

FIG. 8 is a top plan view thereof;

FIG. 9 is a front elevation view thereof;

FIG. 10 is a rear elevation view thereof;

FIG. 11 is a left side view, the right side being a mirror image thereof; and,

FIG. 12 is a front, bottom and left side perspective view thereof.
